METHOD OF AND APPARATUS FOR THE GENERATIVE FORMATION OF SURFACES OF OVATE SECTION

Harold L. Blood, Worcester, Mass., assignor to The Heald Machine Company, Worcester, Mass., a corporation of Massachusetts

Application February 19, 1941, Serial No. 379,619

10 Claims. (Cl. 77—3)

The present invention relates to the direct generation (i. e., without resort to copying from a master or pattern), by machining, boring, grinding or the like, of exterior or interior surfaces that are slightly ovate or noncircular in cross section. Examples of such surfaces are the cylinder bores required for certain fluid motors, pumps, compressors etc. of the rotary type, viz: those wherein the usual eccentrically-mounted rotor or drum has a diametrically slidable vane or piston of substantially one-piece or constant-length construction. The operation of such a vane requires a cylinder bore of approximately the sectional contour defined by a symmetrical limacon curve which is equimetallic in all directions through a point corresponding to the center of the eccentric drum or rotor, namely, the curve which is traced by the ends of a series of equal-length chords all passing through the same interior point, and whose perpendicular bisectors pass through the center of the inscribed circle.

For the formation of a bore surface of such curvature, it has heretofore been proposed to eccentrically rotate the cylinder in a lathe with its drum or rotor axis in alignment with the lathe axis, thus to obtain, by the horizontal component of the cylinder's eccentric motion, the reciprocation of a cutting tool which engages the cylinder bore in the horizontal plane of said lathe axis. Theoretically, this previously proposed method will cause the desired non-circular curvature to be described by the tool point on the eccentrically-rotating work surface; but in the practice of this method, great difficulties are encountered in the cutting action of the tool. One of these difficulties stems from the off-center rotation of the work, which compels the point of cutting to constantly shift between positions far above and far below the cylinder bore axis; these changes of cutting level, relative to the concave surface of the work, involve such extreme variations in the rake and clearance angles of the tool that no uniformity of cutting action is obtainable. Another difficulty of this previously proposed method is the relatively great amplitude of reciprocatory tool travel, over a distance which is double the eccentricity of the bore and drum axes, and thus, far in excess of the actual departure of the desired curve from its inscribed circle—this involving periodically such rapid feeding movements of the tool into the surface of the rotating work that excessive cutting pressures and rapid tool wear are inevitable.

It has also been proposed to hold the work from rotation, and to machine its bore to the desired

non-circular cross-section by a rotary and slidably-mounted cutting tool which, in revolving about an axis corresponding to that of the cylinder's eccentric rotor or drum, is constrained to slide in and out, to give the tool point a non-circular path of the desired curvature. But here again there are wide variations in the rake and clearance angles of the tool; moreover the tool's cutting point is compelled to pass very rapidly over certain portions of the work surface and very slowly over other portions of the work surface, so that no uniformity of cutting action is obtainable.

My invention overcomes all these difficulties, by machining or cutting the work bore to the desired ovate section in a manner which permits the relative rotation between tool and workpiece to take place on the true axis of the workpiece bore, and which allows the tool to have an absolutely uniform cutting speed, with no appreciable variations in its rake and clearance angles; moreover, the reciprocation of the tool is of very small amplitude, at no time exceeding the maximum departure of the desired section from its inscribed circle. Other and further objects and advantages of my invention will more fully appear from the following detailed description, taken in connection with the accompanying illustrative drawings, in which—

Fig. 1 is a sectional view showing the essential elements of a vane type pump or compressor, when a constant-length vane is used.

Fig. 1a is a view similar to Fig. 1, showing a slightly different vane construction.

Fig. 2 is a diagram illustrating the nature of the sectional contour required for a cylinder bore adapted to accommodate a vane of the type shown by Fig. 1.

Fig. 2a is a similar diagram for a cylinder bore adapted to accommodate a vane of the type shown by Fig. 1a.

Fig. 3 is a schematic view, illustrating the principles of my generative method, as applied to the machining of the contour represented by Fig. 2.

Fig. 4 is a view in front elevation of a boring machine organization arranged in accordance with my invention to generate the desired surface contour.

Fig. 5 is a top plan view of the machine of Fig. 4. Fig. 6 is a larger scale fragmentary end elevation of said machine, as viewed from the right Fig. 4.

Fig. 7 is a sectional view, on the line 7—7 of Fig. 6.

Fig. 8 is a large scale front elevation of the tool head of said machine.

Fig. 9 is an end elevation of said head as viewed from the left, Fig. 8.

Like reference characters refer to like parts in the different figures.

I have shown very simply in Fig. 1, the elements of a vane type pump or compressor having the conventional eccentric rotor or drum A, but the latter's vane instead of being the well-known variable-length device for operation in a cylinder chamber of circular cross section, is a constant-length vane B slidable diametrically in said rotor. Such a constant-length vane B requires for its operation a cylinder chamber or bore whose interior boundary surface is slightly non-circular in cross section, the same being typified, for example, by the curve D (Fig. 2) of the limacon order, such as would be traced or generated by the terminal points *a* and *b* of a succession of equal-length chords L, L', etc. (corresponding to the length of the vane), all passing through the same point P (the center of the eccentric rotor) which is at a fixed distance R from the center C of the inscribed circle E; as shown in Fig. 2, each chord's perpendicular bisector *l* passes through said center C.

My improved method of generating the substantial equivalent of this cross-sectional contour D is depicted diagrammatically by Fig. 3, wherein the point P' represents a crank which follows a circular path of radius R' about a center C'; this crank is shown in engagement with a suitable slot *s* of a lever *f*, pivoted to rock, in response to said crank's rotation, about a fulcrum point *b'*; the lever *f* provides at its other end a plane surface *g*, which is at a distance *h* from fulcrum point *b'*. Cooperating with surface *g* is an arcuate surface *J*, provided by a slidably mounted bar *m* carrying a cutting tool whose point is indicated at *t*—the arrangement providing a spring *n* or the like by which to maintain contact of surface *J* with surface *g*. The tool *t* is shown in operative relation to the bore W of a piece of work (such as a pump cylinder of the type shown by Fig. 1) which is revolved about the axis *o* of its bore at the same angular speed as that imparted to the crank P'.

The arcuate surface *J*, Fig. 3, is struck from a center or axis *J'* on such a radius (*k*) that the sum of the distances *h* and *k* is equal to one half the length

$$\left(\frac{L}{2}\right)$$

of the chord or vane L (Fig. 2). Also in Fig. 3, the parts are so proportioned with relation to the dimensions of the curve D, that the distance ratios

$$\frac{C' \text{ to } b'}{R'} \text{ and } \frac{C \text{ to } b}{R}$$

are substantially alike, when the distance C to *b* as shown is nearly at its maximum length.

Under these conditions, in the similar triangles CbP and C'b'P' of Figs. 2 and 3, respectively, the angles at the points *b* and *b'* are the same; also the two right triangles

$$C \left(\frac{L}{2}\right) b \text{ and } b' (h+k)J'$$

are identical, since

$$\frac{L}{2} = h+k$$

Therefore in the angular position of parts shown by Fig. 3, the distance *X* between points *b'* and *J'* equals the distance from center C to point *b*, Fig. 2. Accordingly, if, as shown in Fig. 3, the tool point *t* is spaced from work center *o* by this same distance *X* (equal, in the angular position shown, to the distance from C to *b*), then said tool point, during each single ensuing revolution of the crank P' and work W, will be caused, by the movements of bar *m* in response to rolling of surface *g* on surface *J*, to vary its distance from the work center *o* in nearly the same proportion as the terminal point *b* of chord L varies its distance from center C in tracing the curve D, Fig. 2.

The cross-sectional contour generated in the bore of rotating work W by the tool *t* may vary slightly from the curve D, because of the fact that the fulcrum point *b'* is fixed rather than movable. But the error or deviation is wholly negligible in practice. Actually the angle C'b'P' has the same value as shown in Fig. 3 at four different points in each revolution of the crank, and at each of these points, as demonstrated above, the distance from *o* to *t* exactly equals the distance from C to *b*. This equality also prevails each time the angle C'b'P' passes through zero—making six points where the correspondence is exact. At intermediate points the differences between the angles C'b'P' and CbP are so slight that the deviation from curve D of the contour produced by tool *t* is negligible, being well within practical working tolerances.

The adaptation of the principles above set forth to a machine for generating a surface of revolution having the desired non-circular cross-section, is shown by Figs. 4 to 9 inclusive. As shown in Figs. 4 and 5, said machine provides a suitable base 1, having longitudinal ways, not shown, for the support of a reciprocating table or slide 2. A bridge 3 spanning said ways and said table, supports a head or mounting 4 wherein is suitably journaled a work-rotating spindle 5; the latter carries at one end a suitable holder 6 in which the work W is chucked, and at the other end a pulley 7 which may be connected as shown by a belt 8 to a drive pulley 9 on the shaft 10 of a motor or other prime mover, employed for the rotation of the work W.

The bridge 3 also carries a suitable bracket 11, having spaced bearing portions 12 and 13 wherein are rotatably mounted the sleeves 14 and 15. Slidably received in these rotatable sleeves is the polygonal end portion 16' of an elongated shaft 16, said end portion 16' being slidable endwise through a gear 17 mounted thereon and meshing with a gear 18 of the same size on spindle 5—any suitable means, such as a fixed housing 19 secured to head 4, being employed to hold the gear 17 against shifting endwise with shaft 16, thus to insure the latter's rotation at the same speed as spindle 5.

This provision for endwise movement of shaft 16 grows out of the fact that its other end is supported and carried by the reciprocating table 2, the latter having mounted thereon a suitable bracket 20, providing a housing 21 in axial alignment with said shaft and containing bearings 22 (Fig. 7) for the reduced end 23 of said shaft. Beyond said bearings the shaft has an eccentric pin or crank extension 24, the latter entering and being turnable in a block 25 which is held on said crank by a nut 25'.

The bracket 20 provides suitable housings 26 and 27 for bearings 28 and 29 in which is jour-

nalled, below shaft 16, a rock shaft 30, the latter having an intermediate cut-away portion 31 wherein is secured a hardened pad 32 whose flat working surface, facing downwardly, is on a diameter of said shaft; that is, the shaft axis is contained by said surface, and the latter, at the middle of said shaft's rocking movement occupies the horizontal plane of said axis. Secured to rock shaft 30, as by a pin 33 is the hub 34 of a yoke member 35, the latter extending upwardly around the crank 24, and providing interior parallel guide surfaces 36 and 37 (the latter on a cap 38) in opposed relation. The block 25 has end surfaces (shown by broken lines in Fig. 6) which are in sliding contact with these guide surfaces 36 and 37—whereby at each revolution of shaft 16, said block 25, under the influence of crank 24, gives yoke 35 and with it the attached shaft 30 a back and forth rocking movement, similar to that of lever *f* in the diagram of Fig. 3. Also by analogy with Fig. 3, the center-to-center distance between shafts 16 and 30 and the radius of crank 24 are so chosen and proportioned as to be in the ratio

$$\frac{C \text{ to } b}{R}$$

(Fig. 2) of the curve to be generated.

The bracket 20 of table 2 also supports a trunnion shaft 39, parallel to the rock shaft 30 and offset therefrom a definite distance as hereinafter described. Mounted for rocking movement about the axis 40 of shaft 39 is a bell-crank member 41, having a generally horizontal portion 42 whose free end underlies the rock shaft 30, and having a generally upright portion 43, for the support of a tool, as hereinafter described, adapted to operate in the bore of work W during the latter's rotation by the work spindle 5. The portion or arm 42 has secured thereto, as by suitable bolts 47, an upwardly extending post 44, carrying at the top a hardened wear pad 46 whose convex upper surface, struck from an axis 45, is contacted by the flat under surface of wear pad 32 on rock shaft 30. Such contact is maintained by a spring 48 here shown as seated on bracket 20 and thrusting upwardly against the arm 42. The minimum distance between the axis 45 and the axis of shaft 30 is made equal to one-half the chord length

$$\left(\frac{L}{2}\right)$$

of the curve (Fig. 2) required to be generated.

The axis 40 is equidistant from the axis of work rotation and from the axis of rock shaft 30; that is to say, as shown in Fig. 6, an arc 49 struck from 40 as a center will pass through the axis of shaft 30 (about which rocks the yoke 35) and also through the axis (shown by point 50, Fig. 6) of the work spindle 5. As previously stated, the upright arm 43 of rockable member 41 supports the tool which, by movement of table 2 to the left, Fig. 1, is traversed from one end to the other of the bore of the rotating work W, to generate the desired surface of non-circular cross-section along the full length or depth of said bore.

The point of said tool is indicated in Fig. 6 by numeral 51; the distance of said tool point 51 from work bore axis 50 determines and establishes the spacing (see X Fig. 3) of axis 45 from rocker axis 30, and as this spacing changes slightly, in response to rolling of surface 32 on surface 46, so will the tool point 51 vary its dis-

tance from work axis 50, since the triangles 30, 40, 45 and 50, 40, 51 remain equal, for any given setting or adjustment of the machine, and always swing together.

It will be understood that the tool point 51, in addition to its above-described in and out movements relative to work center 50, is caused by table 2 to traverse the bore of the work, thus to impart the desired cross-sectional contour all the way along said bore. The back and forth travel of the table 2 may, of course, be effected by any suitable means, such as the usual fluid-pressure actuated devices, not shown, whose controls are indicated at 2', Fig. 4.

As shown in Figs. 8 and 9, the tool-supporting arm 43 may be equipped with two tools 52 and 53, the former for a roughing operation and the latter for a subsequent finishing operation, these two operations being performed with a single chucking of the work W. The tools 52 and 53 are arranged 180° apart in a head 54, the latter being movable between two different positions to dispose selectively either the tool 52 or the tool 53 in the working position represented at 51, Fig. 6. To this end, the tool carrying head 54 is mounted on a shaft 55, the latter extending through and being supported by the arm 43 and the latter's attached overhanging bracket 56. A collar 57 secured to shaft 55 keeps the opposing faces of head 54 and bracket 56 in close contact. The head 54 provides index holes 58 and 59 which are 180° apart, and which, by turning of shaft 55 are selectively registerable with a pin 60 slidably mounted in the bracket 56, and pressed toward said head by a spring 61. Entrance of pin 60 into hole 58, as shown in Fig. 8, locks the head 54 in the angular position which makes the roughing tool 52 operative; when it is desired to operate with finishing tool 53, the pin 60 is retracted by means of its handle 62, this allowing the shaft 55 to be turned, by its handle 63, through 180°, to align the other hole 59 with pin 60, for locking the head in the angular position where said finishing tool 53, instead of the roughing tool 52, is operatively associated with the work, in the position 51 of Fig. 6.

Fig. 1a shows the same pump arrangement as Fig. 1, except that the constant-length vane B' has convex, rather than chisel-point, ends. The method and means for generating the interior boundary surface D' of the pump chamber is the same as above described for the surface D of Fig. 1, except as affected by the need to take account of the radius of curvature of the convex ends of the vane. This may be done by utilizing for the cutting operation a grinding wheel or milling cutter having a radius of curvature substantially equal to that of the ends of the vane. Or, a close approximation of the desired contour, by a cutting tool of the type shown at *t* in Fig. 3, can be obtained, as shown in Fig. 2a, if the tool point be set out a distance equal to the vane-end radius, from the curve or contour D² which is traced, as heretofore described, by a constant-length chord L² (the distance between the vane-end centers). The difference in Fig. 2a between the contours D' and D² is due to the angle of contact *z* between the end of the vane and the surface D'.

I claim:

1. Apparatus of the class described, for cutting a workpiece bore to a non-circular section approximating the curve traced by the ends of equal-length chords passing in different direc-
